His Attorney.

UNITED STATES PATENT OFFICE.

EUGENE D. EBY, OF PITTSFIELD, MASSACHUSETTS, ASSIGNOR TO GENERAL ELECTRIC COMPANY, A CORPORATION OF NEW YORK.

ELECTRICAL APPARATUS.

1,415,321.

Specification of Letters Patent.

Patented May 9, 1922.

Application filed October 23, 1919. Serial No. 332,618.

To all whom it may concern:

Be it known that I, EUGENE D. EBY, a citizen of the United States, residing at Pittsfield, in the county of Berkshire, State 5 of Massachusetts, have invented certain new and useful Improvements in Electrical Apparatus, of which the following is a specification.

My invention relates to electrical apparatus and particularly to high tension oil submerged apparatus, and has for its object an improved arrangement of parts which is durable in service and very economical both from a manufacturing and 15 from an operating standpoint.

In apparatus of this type, where a large amount of heat is to be dissipated, it is preferable to make the tanks containing the oil submerged apparatus quite deep, i. e., so 20 that there will be a considerable head of oil above the apparatus itself, in order to provide a heat radiating body of considerable mass. To meet these requirements and yet use as little oil as possible, it is desirable 25 that the tank should have a small perimeter and be relatively deep. The minimum permissible clearance between the sides of the tank and the apparatus therein would hence be the controlling factor in determining the 30 perimeter. This factor however often permits the use of a tank whose mouth is so small that the high tension bushings used to bring in the high voltage leads to the encased apparatus cannot be spaced apart in 35 the ordinary manner sufficiently to have a safe electrical clearance between their lower ends which project into the tank. By my improved arrangement however I mount the high tension bushings very close together 40 in the cover of the tank but pitch them at such angles that their lower and upper ends are further apart within and without the tank than are the bushings at the point where they enter the tank. In this novel 45 manner I am enabled to get the necessary electrical clearance between both ends of the bushings although they are secured relatively close together.

For a more complete understanding of 50 the nature and objects of my invention reference should be had to the following detailed description when taken in connection with the accompanying drawing in which:

Fig. 1 is a side view partly in elevation and 55 partly in section of an encased transformer

showing the high voltage terminal bushings applied in accordance with my invention; and Fig. 2 is a top plan view of the same transformer tank.

Referring now to the drawings, 10 denotes the casing or tank, for the electrical apparatus, here shown as a transformer 11, which is submerged in the oil whose normal level is indicated at S.

The tank 10 is shown as having little 65 clearance, as at 12, between its walls and the windings of the transformer. The cover 13, which is preferably secured to the tank in an oil tight manner, consequently has relatively a small area in which 70 to mount the high voltage bushings; the low voltage bushings (not shown) being preferably placed in pockets formed at suitable points, here indicated under the lobe 14 on the cover 13, in the upper rim of the 75 tank.

The high voltage bushings, which may be of the type shown in U. S. Letters Patent No. 1,304,283 issued in my name on May 20, 1919, are shown at 15 and 15'. These 80 bushings are secured to the cover through openings 16 and 16' which are relatively close together,—so near in fact, where my invention is applied, that the distance between the bushings at this point is less than 85 the minimum electrical clearance permissible between exposed conducting parts which have impressed across them the potential difference designed to be carried by the conductors in the bushings. 90

To provide the necessary electrical clearances between the ends of the bushings, interiorly as well as exteriorly, I have mounted the bushings on the cover, each at an acute angle, as a and a' oppositely disposed in 95 different planes as P_1 and P_2 (Fig. 2) so that while their points of support in the cover are less distant than the minimum electrical clearance distance, yet their upper ends 20 and 20', and their submerged lower 100 ends 21 and 21' are by this arrangement pitched away from each other so that the necessary electrical clearance obtains between such ends.

Cables 22 and 22' are shown as leading 105 from the submerged lower ends 21 and 21' of the bushings to the windings of the transformer 11.

By the use of my invention it is thus seen possible to use a smaller and more economi- 110

cal tank than would be otherwise permissible.

While I have here shown an embodiment of my invention which is, at present, the best means known to me for carrying the same into effect, I would have it understood that this is merely illustrative and that I do not mean to be limited thereby to the precise details here disclosed since obvious alterations thereof will appear to those skilled in this art, nor in the choice of recognized equivalents except as defined in my claims hereunto annexed.

What I claim as new and desire to secure by Letters Patent of the United States, is:

- 15 1. In oil submerged electrical apparatus, the combination with a tank having a cover, of high voltage bushings mounted in said cover making oppositely disposed acute angles with said cover in different planes.
- 20 2. In oil submerged electrical apparatus,

the combination with a tank having a cover, of high voltage bushings mounted in said cover at a distance less than the permissible 25 electrical clearance between the exposed ends of the conductors of said bushings, said bushings having their axes reversely inclined on opposite sides of the cover whereby both their ends diverge sufficiently to 30 provide the necessary electrical clearances.

3. In oil submerged electrical apparatus, the combination with a tank having a cover, of high voltage bushings mounted in said cover at a distance less than the permissible 35 electrical clearance between the exposed ends of the conductors of said bushings, but pitched to make oppositely disposed acute angles with said cover in different planes.

In witness whereof, I have hereunto set 40 my hand, this twentieth day of October, 1919.

EUGENE D. EBY.
